UNITED STATES PATENT OFFICE.

EMILE WAGNER, OF WASHINGTON, DISTRICT OF COLUMBIA.

DESIGN FOR A WATCH-CHARM.

SPECIFICATION forming part of Design No. 24,062, dated February 26, 1895.

Application filed January 23, 1895. Serial No. 535,977. Term of patent 14 years.

To all whom it may concern:

Be it known that I, EMILE WAGNER, a citizen of the United States, residing at Washington, in the District of Columbia, have invented and produced a new and original Design for a Watch-Charm; and I do hereby declare the following to be a full, clear, and exact description of the invention, such as will enable others skilled in the art to which it applies to make and use the same.

This invention relates to a design for a watch-charm, or similar ornamental attachment for watch-chains, and the like, the object being to present a device for this purpose having a novel and attractive shape, and it therefore consists in the newly-designed watch-charm, substantially as will be herein-after described and claimed.

In the annexed drawings illustrating my invention,—Figure 1 is a perspective view of an ornament fashioned in accordance with my new design. Fig. 2 is another perspective view of the same, looking at the other side. Fig. 3 is a top plan view.

Like letters denote like parts in all the figures of the drawings.

A denotes a flat circular disk which forms the base of my newly-designed watch-charm.

Rising above the base A are the forms of a plasterer's trowel B, a pair of compasses or

dividers C, a right-angled square D, and a Roman letter G, which is designated by the reference letter E. These figures are all grouped together as shown. The point b of the trowel B is at the periphery of the disk A, 35 and the trowel is in an inclined position, with its handle b' uppermost. The bottom points of the legs c c of the compasses C are in contact with the periphery of the disk A, while the vertex of said compasses is at the top and is 40 formed with an eye c'. The letter G is inclined with its lower edge at the periphery of disk A, while its upper part is provided with a projection e, which meets the vertex of the compasses C. The handle b' of the trowel B 45 also appears in contact with the joint of the compasses. The right-angle D surmounts the disk centrally and its two legs d d occupy upwardly inclined positions and cross the legs c c of the compasses C. A chain F is 50 shown connected to the eye c'.

What I claim is—

The design for a watch charm as herein described and shown.

In testimony whereof I affix my signature 55 in presence of two witnesses.

EMILE WAGNER.
